Primary Examiner — Terry A Wallace*(74) Attorney, Agent, or Firm* — Robert D. Watson(57) **CLAIM**

The ornamental design for a hand-held inertia nutcracker, as shown and described.

DESCRIPTION

FIG. 1 is a side perspective view of a closed hand-held inertia nutcracker, according to the present invention;

FIG. 2 is a side perspective view of an opened-up hand-held inertia nutcracker and a nut ready to be cracked, thereof;

FIG. 3 is a front perspective view of a hand-held inertia nutcracker, thereof;

FIG. 4 is a top perspective view of a hand-held inertia nutcracker, thereof;

FIG. 5 is a bottom perspective view of a hand-held inertia nutcracker, thereof;

FIG. 6 is a rear perspective view of a hand-held inertia nutcracker, thereof; and,

FIG. 7 is a side perspective view of a hand-held inertia nutcracker being held by a hand, thereof.

The broken lines show a nut ready to be cracked and a hand that is holding the nutcracker, and they are for illustrative purposes only. The broken lines form no part of the claimed design.
